UNITED STATES PATENT OFFICE

FRANK E. WOLCOTT, OF WEST HARTFORD, CONNECTICUT, ASSIGNOR TO THE SILEX COMPANY, A CORPORATION OF CONNECTICUT

DESIGN FOR A HEATER STAND FOR COFFEE MAKERS

Application filed January 26, 1932. Serial No. 42,630. Term of patent 14 years.

To all whom it may concern:

Be it known that I, FRANK E. WOLCOTT, a citizen of the United States, residing at West Hartford, in the county of Hartford and State of Connecticut, have invented a certain new, original, and ornamental Design for a Heater Stand for Coffee Makers, of which the following is a specification, reference being had to the accompanying drawing, forming part thereof.

In the drawing,—

Figure 1 is a side elevation of the article, showing my new design, the tray being shown partially broken away, and

Figure 2 is a plan view of the same.

I claim:—

The ornamental design for a heater stand for coffee makers, substantially as shown and described.

In testimony whereof I affix my signature.

FRANK E. WOLCOTT.
